United States Patent Office

Des. 221,939

Patented Sept. 21, 1971

221,939

CHAIR

Morris F. Fisher, Carmel, Ind., assignor to Mohasco Industries, Inc., Amsterdam, N.Y.

Filed Nov. 21, 1969, Ser. No. 20,219

Term of patent 14 years

Int. Cl. D6—02

U.S. Cl. D15—11

The figure is a perspective view of a chair illustrating my new design. The back of the chair is conventionally plain while the side not shown is substantially identical to the side shown, the handle on the side shown not being present on the side not shown.

The chair of the instant invention is characterized by the curvature of the arms and back together with the tufted seat and back, all as shown.

I claim:

The ornamental design for a chair, substantially as shown and described.
